UNITED STATES PATENT OFFICE.

JOSEPH TRUSCH, OF PORTAGE, PENNSYLVANIA.

SWITCH STAND.

Application filed March 19, 1927. Serial No. 176,703.

This invention has reference to switches, and more particularly to a device designed to control the movements of movable switch points of a mine track.

5 The primary object of the invention is to provide means for permitting the wheels of a car passing over the track in one direction, to move the switch points to permit the car to pass over the rails without danger of 10 derailment.

A still further object of the invention is to provide means whereby the switch points may be manually operated to set the switch.

With the foregoing and other objects in 15 view which will appear as the description proceeds, the invention resides in the combination and arrangement of parts and in the details of construction hereinafter described and claimed, it being understood that 20 changes in the precise embodiment of the invention herein disclosed, may be made within the scope of what is claimed, without departing from the spirit of the invention.

25 Referring to the drawing:

Figure 1 is a plan view illustrating a switch constructed in accordance with the invention.

Figure 2 is a sectional view taken on line 2-2 of Figure 1.

30 Figure 3 is a sectional view taken at right angles to Figure 2.

Referring to the drawing in detail, the reference character 5 designates the rails of a mine track, and the reference character 6 35 designates the movable points or sections of a switch.

The rails are supported on the ties 7 which also act as a support for the switch box 8, the ties being shown as exceptionally long 40 and extended appreciable distances beyond the rails.

The switch box 8 is provided with lateral flanges 9 that rest on the ties 7, the flanges being supplied with openings to receive 45 bolts, not shown for securing the switch box in position. The movable members 6 are actuated by means of the bar 10, which is provided with upstanding pins 11 and 12 respectively that engage the inner edges of 50 the movable members 6 so that movement of the bar 10 will result in a relative movement of the movable members 6 to set the switch or to return the switch to its initial 55 position after a car has passed thereover.

Connected with the bar 10 is an operating

lever 13 that has a forked end 14 connected with the ear 15 that extends upwardly from the operating lever 16 at a point in spaced relation with the inner end of the lever.

This lever 16 has a bifurcated end 17 provided with openings to accommodate the shaft 18 positioned in the inwardly extended sections 19 of the T-shaped members 20, so that the operating lever 16 may be swung upwardly from a position as shown by Figure 1 to a position so that the lever 16 rests in a notch formed in the opposite end of the switch box, thereby operating the movable switch section.

The T-shaped members 19 embody tubular sections 21 that accommodate the rods 22 arranged in spaced relation with each other and supported within the switch box, the ends of the rods extending through the end walls of the switch box. Mounted on these 75 rods are coiled springs 23, which bear against the ends of the tubular members 20 that are mounted for slidable movement on the rods, the springs acting to normally urge the tubular members to their initial positions.

A weighted handle indicated at 24 is provided at the outer end of the lever 16 and affords means whereby the switch may be manually operated. From the foregoing it will be obvious that when the switch is set in a manner as shown by Figure 1, a car moving in the direction of the arrows as shown by Figure 1 will move into engagement with the movable switch rails moving them against the tension of the springs, and allowing the car to pass over the rails, with the result that the springs will return the rails and switch operating mechanism to their initial positions after the car has passed thereover.

I claim:

1. In combination with the movable switch rails of a railway switch, a bar connected with the switch rails for moving the switch rails, a link connected with the bar, a switch box, rods supported within the switch box, tubular members mounted on the rods, coiled springs on the rods and engaging the ends of the tubular members for normally urging the tubular members to their initial positions and means for operating the tubular members and bar and link for setting the switch.

2. In combination with the movable rails of a railway switch, a switch box, rods mounted

within the switch box, T-shaped members shaped members to their initial positions, and including tubular end members, the tubular end members being mounted on the rods, means for transmitting movement of the T-shaped members to the switch rails. In testimony that I claim the foregoing as a shaft mounted in the T-shaped members, 10 an operating lever mounted for movement on the shaft, said lever having an upstanding ear, means for normally urging the T-

my own, I have hereto affixed my signature.

JOSEPH TRUSCH.
